CLAIM

The ornamental design for a fragrance bottle and cap, substantially as shown and described.

DESCRIPTION

FIG. 1 is a top, front, and right side view of a first embodiment of a fragrance bottle and cap showing our new design;

FIG. 2 is a front elevation view thereof, the rear elevation view being a mirror image thereof;

FIG. 3 is a right side elevation view thereof, the left side elevation view being a mirror image thereof;

FIG. 4 is a top plan view thereof;

FIG. 5 is a rear view thereof;

FIG. 6 is a top, front, and right side view of a second embodiment of a fragrance bottle and cap showing our new design;

FIG. 7 is a front elevation view thereof, the rear elevation view being a mirror image thereof;

FIG. 8 is a right side elevation view thereof, the left side elevation view being a mirror image thereof;

FIG. 9 is a top plan view thereof; and,

FIG. 10 is a rear view thereof.
